Primary Examiner — Melanie H Tung*Assistant Examiner* — Lavone D Tabor*(74) Attorney, Agent, or Firm* — Ryan M. Flandro(57) **CLAIM**

The ornamental design for an oral care implement, as shown and described.

DESCRIPTION

FIG. 1 is a right front perspective view of an oral care implement according to the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines showing the head and the features on the rear of the handle illustrate portions of the oral care implement that form no part of the claimed design.

1 Claim, 4 Drawing Sheets(56)
